UNITED STATES PATENT OFFICE.

RODGER A. BIRT, OF BELOIT, KANSAS, ASSIGNOR OF ONE-HALF TO LESTER L. ENSIGN,
OF SYLVAN GROVE, KANSAS.

CLOTHES DRAINER.

Application filed June 19, 1924. Serial No. 721,093.

This invention appertains to clothes boilers and the primary object of the invention is to provide a novel attachment for clothes boilers for facilitating the draining of the 5 clothes and for removing the clothes from the boiler after the boiling process.

A further object of the invention is the provision of a perforated false bottom or plate detachably associated with the boiler 10 and novel means for holding the plate adjacent to the bottom of the boiler to permit the clothes to be conveniently boiled and novel means for holding the plate in a raised 15 position adjacent to the upper end of the boiler, so that the clothes can be readily drained and conveniently moved from the boiler without any danger to the person handling the clothes.

A further object of the invention is to provide a novel attachment for clothes boilers of the above character, which will be durable 20 and efficient in use, one that will be simple and easy to manufacture and one which can be placed upon the market and incorporated 25 with an ordinary clothes boiler at a small cost.

With these and other objects in view, the invention consists in the novel construction, arrangement and formation of parts, as will 30 be hereinafter more specifically described, claimed, and illustrated in the accompanying drawings, in which drawings,

Figure 1, is a longitudinal sectional view showing the attachment in its lowered position in a clothes boiler,

Figure 2, is a horizontal section taken on the line 2—2 of Figure 1, illustrating the bottom plate of the attachment,

Figure 3, is a transverse sectional view 40 through the attachment, illustrating the novel member carried by the end of the plate or false bottom,

Figure 4 is a detail view of one of the lifting rods showing a modified form thereof.

Referring to the drawings in detail where- 45 in similar reference characters designate corresponding parts throughout the several views the letter A generally indicates a clothes boiler and B the improved attach- 50 ment therefor.

The clothes boiler A is of the ordinary or any preferred character and has been shown to illustrate the use of the improved attach- 55 ment and as shown embodies a bottom wall 5, end walls 6, and side walls 7.

The improved attachment B comprises a plate or false bottom 10 which can be formed from sheet metal of the desired gauge. The plate or false bottom 10 is of substantially the same size and configuration as the boiler 60 A and is provided with a plurality of drain openings 11, the purpose of which will be hereinafter more fully described.

In order to add rigidity to the plate 10 the edges thereof are preferably rolled 65 around a reenforcing rod or wire 12, as at 13.

The ends of the plate 10 has secured thereto supporting rods 14, 16 and 17. The rods 14 are arranged at the longitudinal center of the plate while the rods 16 and 17 70 diverge outwardly from the upper end of the rod 14 and engage the plate in spaced relation to the rod 14. While these rods 14, 16 and 17 can be secured to the plate in any desired way, I have shown the lower ends 75 thereof provided with loops 18 which extend through the plate 10 and around the reenforcing rod or wire 12. The upper ends of the rods are secured to retaining hooks 19 which are adapted to engage the upper 80 edges of the end walls 6 of the boiler as will be hereinafter more fully described. As shown these hooks 19 are provided with an intermediate bill portion 20 and upper and lower terminal eyes 21 and 22. The lower 85 eye 22 receives the upper ends of the rods 14, 16 and 17 while the upper eye 21 receives a supporting rod 23. The rod 23 adjacent to its upper end is first bent back to provide a hook 24 and then upwardly as at 25 and then again bent to provide a handle 26.

In use of the improved attachment the same is placed in the boiler as shown in Figure 1, of the drawing with the upper hook 24 arranged over the upper edges of the end 90 walls 6. This will hold the plate or false bottom 10 in spaced relation, but adjacent to the bottom wall 5 of the boiler. The clothes can now be placed in the boiler for the usual boiling process and it can be seen that as the clothes are held in spaced relation to the bottom wall 5 that the burning or scorching thereof is precluded. After the clothes have boiled and it is desired to remove the same from the boiler the handles 100 26 can be grasped and the plate or false bottom 10 moved upwardly and the hooks 20 placed over the upper edges of the end walls 6. This will hold the plate or false bottom 10 in a raised elevated position above the 110

water level in the boiler and it is obvious that all of the water will be permitted to drain off of the clothes through the openings, 11 in the said plate. As the clothes will be held in elevated position, the same can be conveniently moved from the boiler after the water has drained therefrom.

If so desired a plurality of hooks 27 can be formed in the rods 23 so that the plate 10 or false bottom 10 can be raised in a step by step movement if so desired.

Changes as in detail may be made without departing from the spirit or the scope of this invention, but,

13. What I claim as new is:—

In a combination with a wash boiler and

a perforated false bottom arranged therein, an inverted V-shaped member attached to each end of the false bottom, a hook connected to each of the V-shaped members and terminating in an eye at its upper end, a length of rod engaged in each of the eyes, a hook formed at the upper end of each of the lengths of rod and normally engaged with the upper edge of the wash boiler, the first mentioned hooks being adapted to engage the upper edge of the wash boiler when the false bottom is disposed adjacent to the upper edge of the boiler.

In testimony whereof I affix my signature.

RODGER A. BIRT.
